(57) **CLAIM**

The ornamental design for a hearing aid as shown and described.

DESCRIPTION

1. Hearing aid

1.1 : Front

1.2 : Back

1.3 : Left

1.4 : Right

1.5 : Top

1.6 : Bottom

1.7 : Perspective view (front, top, left)

1.8 : Perspective view (back, right)

The broken lines showing a rounded rectangle is for the purpose of illustrating a connection point of the hearing aid and forms no part of the claimed design.

The characteristic features of the design lie in the shape of the hearing aid as shown.

1 Claim, 8 Drawing Sheets(56)
